UNITED STATES PATENT OFFICE.

JOSEPH ASKINS, OF LIMA, OHIO.

STEAM-RADIATOR.

SPECIFICATION forming part of Letters Patent No. 367,083, dated July 26, 1887.

Application filed December 18, 1886. Serial No. 221,992. (No model.)

To all whom it may concern:

Be it known that I, JOSEPH ASKINS, a citizen of the United States, and a resident of Lima, in the county of Allen and State of Ohio, have 5 invented a new and useful Improvement in Steam-Radiators, of which the following is a specification.

My invention is an improvement in steam-radiators.

10 Figure 1 is a perspective of a series of loops or radiators united. Fig. 2 is a vertical sectional view of one of the radiators.

15 My radiator is composed of a number of sections or loops, cast separately and united near the bottom by nipples, and bolted together near the top.

The construction and operation of my radiator-loop are as follows:

20 The main part A is cast in one piece having a hollow interior forming the chambers B C M and passage Q. Near the bottom of chamber M is a port for the admission of steam. There is also a corresponding port on the opposite side, so that when a number of loops are 25 combined they can be connected by ordinary pipe-nipples. Through the top and bottom of chambers B C are holes, into which the open-ended wrought-iron tubes E D are inserted and secured. The lower ends of the tubes are screwed 30 securely into the holes in the base, while the upper ends are secured by nut H, having an asbestos washer underneath it and countersunk into the top of the loop or radiator. Any number of these loops may be used to 35 form a radiator of any desired size or capacity, by placing them face to face and bolting them together through the holes in lug K, the bottoms being first secured together by connecting pipes or nipples screwed into the holes or 40 ports in the chamber M. On the faces at the top will be seen notches R and lugs S. After two of the loops or radiators have been se-

cured together by pipes M at the bottom, they are sprung apart slightly at the top and the lug S fitted into the notch R, when they are 45 further secured by a bolt passed through lugs K.

Steam is admitted through pipe L into chamber M, whence it passes up through throats N N', chambers B C, and through passage Q. 50 The contact of the hot steam on all sides of the pipes D E heats the air in the pipes, when it rises and escapes at the top, causing a continuous circulation of air through the tubes, the cold air being taken from the floor, heated, 55 and passed off into the room again from the tops of the pipes.

The throat N' is only about half the size of throat N, and while steam has equally free entrance to both, the greater quantity passes 60 through the throat N, establishing a circulation in the chambers, filling the chamber B first and flowing into chamber C through the passage Q.

What I claim is—
1. In a steam-radiator, the combination, with 65 the single-piece casting A, forming the steam-chambers, of the wrought-iron open-ended tubes secured rigidly in the bottom of the casting, but passing through the casting at the top and secured by the countersunk nut H at the top, as and for the purpose set forth.

2. The combination, with the casting A, having the inlet and outlet pipes L and the wrought-iron pipes E, secured rigidly in the 75 bottom, but passing through the casting at the top of the nut H, and elastic asbestos washer I, that allows for the unequal expansion of the wrought and cast iron parts, as and for the purpose set forth.

JOSEPH ASKINS.
